UNITED STATES PATENT OFFICE.

EDWARD A. KING AND ASMUS J. CARR, OF CHICAGO, ILLINOIS; SAID KING
ASSIGNOR TO SAID CARR.

AWNINg-BRACE.

SPECIFICATION forming part of Letters Patent No. 445,718, dated February 3, 1891.

Application filed September 6, 1890. Serial No. 364,176. (No model.)

To all whom it may concern:

Be it known that we, EDWARD A. KING and ASMUS J. CARR, citizens of the United States, residing at Chicago, in the county of Cook and State of Illinois, have invented a new and useful Improvement in Awning-Braces, of which the following is a specification.

Our invention relates to a brace or stay for the ordinary iron-framed awning now in general use, and is designed to brace or stay the same firmly in position when distended, and thereby to prevent the awning from rising and falling in the wind. We attain these objects by the mechanism illustrated in the accompanying drawings, in which—

Figure 1 is an awning with the brace in position, the awning being distended. Fig. 2 is a vertical section of the attaching parts of the brace, showing the working parts thereof; and Fig. 3 is a cross-section of the same.

Like letters refer to like parts in the several views.

A is the awning.

B is the rod or frame which distends the awning A from the wall W, to which it is attached.

C is the hinge on which the awning-frame B turns in raising and lowering the awning A.

D D are dead-eyes or pulleys through which the rope R works in raising the awning A when pulled down at the end E.

F is a lug fixed to the rod B or frame of the awning A.

G is the arm of the awning-brace, which arm is attached to the wall W by the hinge J.

H is a pivoted sleeve attached to the arm G of the brace by the hinge-joint L, and which head H is freely movable along the rod B.

K is a clutch fixed to the sleeve H by the hinge-joint N, and by means of which the movable sleeve H is held against the lug F, when it is so desired.

R is a rope (provided with a ring or knot O) attached to the clutch K and operating through the dead-eyes or pulleys D D to lift the clutch K and to raise the awning A.

It will be readily seen that if the rope R is pulled down at the end E the rope R will draw through the dead-eyes or pulleys D D until obstructed by the ring or knot O, which movement is sufficient to lift the clutch K

from the lug F, and if the pulling of the rope R is continued the awning A will be raised against the wall W, to which it is attached, the sleeve H moving outward along the rod B as the outer end of the rod B is brought toward the wall W. It will also be further seen that when it is desired that the awning A be distended if the end E of the rope R be loosened the rod B or the frame of the awning A will of its own weight fall outward from the wall W and the sleeves H will move inward along the rod B until the clutch K, aided by the coil-spring S, catches over the lug F, when the awning A will be held firmly in its distended position and be prevented from being beaten by the wind, saving the awning from destruction and the owner of the awning from annoyance as well as expense.

It will be further seen that our invention can be attached and detached readily from the awning now in general use, thereby saving the expense of preparing a particular form of awning-frame and giving it a portable character.

What we claim as our invention, and desire secured by Letters Patent of the United States, is—

1. In an awning-brace, the combination of the rod B, provided with the stop F, and the rod G, having at one end the attaching-hinge J and at the other end the pivoted sleeve H, adapted to reciprocate on the rod B and provided with a pivoted spring-clutch K, adapted to engage the stop F, substantially as set forth.

2. In an awning-brace, the combination of the rod B, provided with the stop F, and the rod G, having at one end the attaching-hinge J and at the other end the pivoted sleeve H, adapted to reciprocate on the rod B and provided with the pivoted spring-clutch K, adapted to engage the stop F, all operated by means of a cord R, attached to the clutch K and passing through the dead-eyes D D, all substantially as set forth.

EDWARD A. KING.
ASMUS J. CARR.
